Primary Examiner — George D. Kirschbaum*Assistant Examiner* — Lacey Chey Bowman*(74) Attorney, Agent, or Firm* — Myers Wolin, LLC(57) **CLAIM**

The ornamental design for an interchangeable lens for camera as shown and described.

DESCRIPTION

FIG. 1 is a perspective view of an interchangeable lens for camera, showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken lines in the drawings are for the purpose of illustrating portions of the interchangeable lens for camera that form no part of the claimed design.

1 Claim, 7 Drawing Sheets(56)
